UNITED STATES PATENT OFFICE.

BENJAMIN F. JOHNSTON, OF TORONTO, ONTARIO, CANADA.

INCUBATOR.

1,319,342.

Specification of Letters Patent.

Patented Oct. 21, 1919.

Application filed May 17, 1919. Serial No. 297,837.

To all whom it may concern:

Be it known that I, BENJAMIN F. JOHNSTON, of the city of Toronto, in the county of York, Province of Ontario, Canada, have 5 invented certain new and useful Improvements in Incubators, of which the following is a specification.

In devising this incubator my object has 10 been to provide a cheap, simple and easily operated incubator in which the turning of the eggs is greatly facilitated.

I attain my object by means of constructions hereinafter described and illustrated in the accompanying drawings in which—

15 Figure 1 is a perspective view of an incubator constructed in accordance with my invention; and

Fig. 2 a sectional detail of one of the thermostats.

20 In the drawings like numerals of reference indicate corresponding parts in the different figures.

The incubator casing is formed in two parts 1 and 2, so shaped that when brought 25 together they form a cylinder. These halves are hinged together along one edge and are provided with one or more catches 2' secured to one half and adapted to engage in keepers on the other half. These keepers 30 may be slots 3 as shown. The part 1 of the incubator casing in section is slightly greater than a semi-circle, and the bail 4 is journaled on trunnions 5 secured thereto, the trunnions being located in alignment with 35 the center of gravity of the device, so that it will hang from the bail with either end up.

Axially of the casing is located the rod 6, which is secured to the ends of the part 40 2 of the casing by means of nuts 7. To secure stiffness with lightness, this central rod may be formed of a tube, and is threaded from end to end to carry the trays 8.

These trays 8 are formed with hubs 9 threaded to screw on the rod 6, and are also 45 preferably provided with the rims 10. These trays are preferably perforated or formed of heavy woven wire. The trays are used in pairs with the rims 10 of each pair facing one another, the eggs being held 50 between such pairs of trays. The trays being substantially similar, the device may be used with either end up and turned end for end whenever necessary to invert the eggs.

At any time the rod 6 and the trays carried 55 thereby may be removed by slackening the nuts 7.

Electrical heating apparatus is preferably provided. This may comprise a coil 11 located within the casing at one end. The wires for the coil are led in through the 60 trunnions 5, one or both of which being formed hollow for that purpose. If preferred, a heating coil 11 may be located at each end of the casing. A deflecting plate 12 should be placed between each heating coil 65 and the adjacent trays to prevent undue heating thereof by radiation from the coil. As the heated air tends to rise, it will usually be preferable to use the heating coil located at the lower end of the casing, cutting 70 out the coil at the opposite end.

A thermometer 19 may be located along the eggs, for example, those contained in the middle pair of trays, which thermometer may be read through the glazed door 13 75 which closes an opening in one part of the casing. Another door 14 is provided closing an opening in the other half of the casing, which door is provided with pockets to receive damp sponges.

The temperature of the incubator is regulated by thermostats 15, one located at each end of the casing, which thermostats may be of the type shown in Fig. 2. The thermostat comprises two flaps 16 connected together and pivoted at 17 adjacent a hole formed in the cover. The parts are so balanced that the thermostat at the bottom will remain open providing ingress for cool air whenever the thermostat at the top opens. 90 If the temperature in the incubator rises beyond a predetermined degree, the heated air will raise the flap 16 of the upper thermostat which is covering the hole controlled by the upper thermostat and will permit a 95 sufficient amount of the heated air to escape to permit the temperature falling to the desired degree.

What I claim as my invention is:—

1. As an incubator, a cylindrical casing 100 formed in semi-cylindrical halves hinged together; a center rod secured in axial position to the ends of one half; trays supported on said center rod; covers adjustable to and from the trays; means for supporting the 105 cylinder so that it may be tilted to bring either end uppermost; and means for heating the interior.

2. An incubator constructed as set forth in claim 1 in which the center rod is threaded and the trays and covers are threaded to screw on the center rod,

3. An incubator constructed as set forth in claim 1 in which one half of the casing is provided with a door adapted to hold a sponge at its inner side and the other half of the casing with a glazed door for inspection purposes.
4. As an incubator, a cylindrical casing adapted to open up longitudinally; a center rod secured in axial position in the casing; disk-shaped trays and covers therefor carried on the center rod relatively adjustable to and from one another on the center rod;
- means for heating the interior of the casing; and trunnions at opposite sides of the casing whereby it may be supported so that it may be turned end for end.
5. An incubator constructed as set forth in claim 4 in which electric heating means are provided, one of the trunnions being made hollow for the passage of electric wires.

Signed at Toronto, Canada, this 30th day of April, 1919.

BENJAMIN F. JOHNSTON.
